FLUID MOTOR

Matthew H. Loughridge, Bogota, N. J.; William R. Lockridge, administrator of said Matthew H. Loughridge, deceased

Application January 24, 1940, Serial No. 315,300

10 Claims. (Cl. 253—1)

This invention relates to control and selective apparatus and the method of operating the same and particularly to a novel type of fluid motor used in connection therewith, and is intended for general use. The invention includes a stator or stationary part and a rotor or moving part, in which the rotor may be driven by a fluid pressure impeller supplied with pressure from the stator and the selective operation is obtained by stopping the rotor in any predetermined position by the operation of a key or other system of control. The stopping effect is produced by an air jet between the stator and the rotor and for this purpose the stator is provided with a plurality of radially arranged air conduits and the rotor is provided with a single air nozzle which registers with each of the air conduits or nozzles of the stator as it rotates. As soon as the nozzle of the rotor aligns with the nozzle of the stator, which is supplied with fluid pressure, the fluid jet stops the rotor and holds it in this position until the flow to the jet ceases. The system operates with air pressure or with hydraulic pressure according to the purpose to which it is applied. Its operation will be understood by considering that a fluid pressure jet has inertia and has direction. When the jet is forced through a nozzle it acquires the direction of the nozzle and after it leaves the nozzle it resists efforts to change its direction, hence, when the nozzle of the rotor aligns with the nozzle of the stator the pressure jet flows in a straight line through the combined nozzles and its inertia resists any movement of the rotor that takes it out of this aligned position. When hydraulic fluid is used to operate the system the jet has a much greater resistance than an air jet would have and is capable of controlling a heavier mechanism. This provides a driving force and a stopping force between the stator and the rotor without mechanical connections and enables these forces to be applied in a variety of ways without complicating the apparatus.

This invention may be applied to the same general uses as that shown in application Serial No. 282,833, filed July 4, 1939, and adapted for electric operation.

The invention will be more particularly understood from the following specification and the accompanying drawing, showing the principles of operation and a variety of applications, and, in which:

Fig. 1 is a front elevation of a stator and rotor arranged for pneumatic operation according to the invention;

Fig. 2 is a sectional elevation on line 2—2 of Fig. 1;

Fig. 3 is a cross section on line 3—3 of Fig. 2;

Fig. 4 is a cross section on line 4—4 of Fig. 2;

Fig. 5 is a cross section on line 5—5 of Fig. 2; and

Fig. 6 is a diagram, partly sectioned, showing the controlling system;

Fig. 7 is a sectional detail, modified from Fig. 2.

The system comprises a stator and a rotor forming a fluid motor and by means of air pressure the rotor is driven in either direction and by means of an air jet it is stopped in any predetermined position. The driving action is secured by a turbine construction between the stator and the rotor in which air is applied through the stator to act upon vanes in the rotor to drive it in one direction, and air from another conduit in the stator is arranged to apply air pressure to the vanes of the rotor in the opposite direction, thereby securing a reverse drive.

The stator is provided with a number of radially spaced air jets, through each of which a stream of air may be forced. This air stream is applied to a channel in the rotor which has a smooth interior except at the reference point where an aperture is provided through the rotor that registers with each of the jets in the stator as the rotor rotates. Only one jet can be energized by an air stream at a time so that as soon as the aperture of the rotor registers with an energized jet the air stream is sufficiently powerful to stop the rotor and hold it in this registering position.

The air conduits to the stator are controlled by the keys of a keyboard so that only one conduit may be open to the air supply at a time. The control includes a reversing valve whereby air pressure may be applied to either of the propelling conduits of the air turbine and thus enabling the rotor to be driven in either direction by the operation of this valve. The control system may, further, embody a regulating valve operated by the back pressure of the air system supplied to the air jets for cutting off the air supply to the driving turbine when stop conditions are established.

The system is fully reversible in its structure and operation and is so contemplated in the specification and claims.

In the drawing, Figs. 1 to 6, 11 is the stator disc which is provided with a central boss 12 upon which the rotor disc 14 is mounted through the ball bearings 15. The rotor disc 14 carries the

rotor or rim 16 which is spaced by the air gap 17 from the stator 13, supported on disc 11. Rotor 16 is provided with the annular channel 18 which has the aperture 19 at the reference point, which aperture corresponds in diameter with the diameter of the conduits 25, through which the air jet for stopping the rotor is provided. The aperture 19 is provided with a counterbored orifice 21 adjacent to the conduit 25 so that the air jet is collected by the orifice 21 and passes through the orifice 19 in a straight line from the conduit 25 and thereby aligns 19 with 25 and holds them in this position while the air jet is continued. The flared opening at 21 engages the pressure jet when 19 is out of alignment with the nozzle 25 to bring the nozzle into alignment. When the nozzles 25 and 19 are aligned the pressure jet passes straight through without obstruction, as would occur when the rotor is stationary. Any movement of the rotor in either direction from this position engages the walls of the flared opening 21 with the pressure jet and restores alignment. The air supplied through any one of the conduits 25 is received in the channel 18 and is free to return on all of the other conduits 25 which are open until their keys are operated. In order to retard the motion of 16, if it is operating at speed as it approaches the reference point, the conduit 18 is formed on an inclined plane indicated at 20. This produces a damping action on the rotation of 16, as it approaches the stopping position. Stopping the rotor by aligning the nozzles so that the pressure jet has a straight passage in the rotor and stator has been referred to as a "locking" engagement which implies that these parts are rigidly held together to the extent of the force supplied by the pressure jet.

The rotor 16 has a channel 22 which is provided with cross vanes or blades 23, Figs. 3 and 4. The stator 13 is provided with a channel 36 which connects with the air pipe 39 and with another channel 37 which connects with the air pipe 40. As shown in the drawing these channels are made on the face of the stator and are covered by the annular plate 38. The outer channel 36 is provided with a series of inclined apertures 42 aligning with the channel 22, Fig. 4, thereby providing an air blast from 36 through each channel acting upon the vanes 23 as a turbine to drive the rotor in one direction. The inner channel 37 connects by the inclined passages 41, Fig. 3, with the channel 22 to provide an impelling air force acting upon the vanes 23 from the air in channel 37. It will be noted from Figs. 3 and 4 that the direction of the air conduits 42 is reversed with respect to the air conduits 41 with the result that the air delivered by the tube 39 drives the rotor in one direction as indicated by the arrow 34 and the air delivered to tube 40 drives the rotor in the opposite direction as indicated by the arrow in Fig. 3.

A three-way valve 43 controls the air supply from the pipe 44 to the tubes 39 and 40. When the valve is in the position shown in the drawing, Fig. 6, air is supplied to tube 40 and is cut off from tube 39 and when the valve 43 receives a quarter turn in the direction of the arrow, air is cut off from tube 40 and supplied to tube 39, thereby reversing the direction of the drive by the operation of valve 43.

Air may be supplied from an air compressor indicated by 29 and driven by motor 30 and supplied to the air pipe 28. This air is fed through a restricted orifice 27 to the pipe 26 which connects to the row of control pipes 25, through a

valve 31 provided on each pipe. This is a three-way valve which, in the normal position, exhausts each pipe 25 through a port 32a, but when the keys or operating member 31 is depressed, the valve 32 is rotated for a quarter-turn to shut off the exhaust 32a and to connect the pipe 25 with the air supply pipe 26. In the operation of the system only one key or valve is operated at a time and before a second key is operated the previous key is returned to its normal position in any suitable manner, as by a restoring spring on the key itself or by an interlocking plate provided for this purpose between the keys, both of which arrangements are commonly used for this purpose and therefore not shown in the drawing.

In Fig. 6, to the left, a pair of keys or valves 32 and 33 are shown connecting the air pipe 26 with the air conduit 25'. When the valves are in the position shown the air flows through valve 33, pipe 34 and valve 32 to pipe 25'. When valve 32 is restored to its normal position, pipe 35 is connected with 25' and when valve 33 is operated pipe 26 is connected with 35 and pipe 34 is cut off. In this application both keys or valves 32 and 33 operate the system to stop the rotor in the same place. That is, each of these keys produce a corresponding result or total and bring the rotor into the proper registering position for these totals.

The application of the system enables a relatively powerful air blast to be used in the nozzle which is used for stopping the rotor and this air blast can be designed to stop the rotor while the impeller is in operation. In some cases, however, it may be desirable to shut off the impelling force if the rotor is to be retained in the selected position in which it was stopped. One method of securing this result is obtained by the valve 45 which controls the air supply between 28 and 44. This valve is controlled by a piston 47, acting against a spring 48, which holds the piston valve 46 in position to blank the ports from the air pipe 28' to pipe 44. When, however, air pressure is supplied to pipe 49 to act on piston 47 against spring 48, the piston valve 46 is raised and thereby connects the air supply to pipe 44. When the system is in its normal position, with all the keys 31 closed to the air supply pipe 36, air pressure is built up in pipe 49 to open valve 46 and to supply air to the driving conduits 39 or 40, thereby providing continuous rotation for the rotor.

When any of the keys 31 is operated, an air outlet is provided on pipe 26, through pipe 25, to the nozzle in the stator and to the annular groove 18 in the rotor. This air can escape freely and without obstruction when the nozzle in the stator registers with the nozzle 19 in the rotor. At other times the air does not have a free passage from the nozzle of the stator but instead meets with a retarding condition in the groove 18 as it is dissipated through the air gap 17, or back through the other conduits 25 to the open valves which control these conduits. When the nozzle of the stator and the rotor are in register the air pressure in pipe 26 is reduced to a greater extent than it can be supplied through the restricted passage 27 and this reduction in air pressure, in tube 49 enables the spring 48 to close the valve 46 of 45 and thereby shut off the supply of air for driving the rotor. When the air through the nozzle from the pipe 25 does not have a free passage the back pressure established under these conditions operates to open valve 46 and to permit the driving force to act on the rotor until it is brought into the registering position. If it

is desired to increase the stopping force, the arrangement in Fig. 7 may be adopted in which a pair of nozzles is brought into the stopping position at the same time and controlled by the same key. For this purpose the additional nozzle 25a in the stator 13 registers with the nozzle 19a in the rotor 16 in parallel with the nozzles 25 and 19 to produce an increased stopping effect.

The fundamental principles of the invention are illustrated in Figs. 1 to 5 and one mode of operation is shown in Fig. 6. The actual application of the invention for any specific purpose must be designed for each particular use. If the system is to be applied to a registering device that selectively registers marks in accordance with the operation of the keys, it may be arranged to operate by suction instead of air pressure for driving the rotor and the rotor may be provided with radially spaced blades 23 in the groove 22, adapted to be propelled by air force in either direction.

It should be understood that the impelling system is independent of the stopping system except insofar as they are co-ordinated in the control. The impelling system therefore, may be adapted to use electric power while the stopping system is pneumatic. In either case a mechanical connection for driving purposes between the stator and the rotor is avoided.

When the system is adapted to operate relatively heavy mechanisms, such as may be used in textile machines, or in machine tools for positioning turret heads and the like, the driving force and the stopping force should be increased and the use of hydraulic fluid pressure instead of air pressure may in some cases be desirable and is fully contemplated by the invention.

The operation of the system depends upon the pressures used to accelerate speed in the driving and reliability in the stopping and it depends upon the shape of the nozzles which should be designed for the particular pressures contemplated. In the application of the stopping effect it should be noted that in the stator 13 the nozzle 25 is provided and in the rotor 16 the nozzle 19 is provided which when aligned form a single nozzle for the air jet in a straight passage between these parts.

It should be noted that the stopping effect has no tendency to drive the rotor in either direction and is not in any sense a reverse drive. The moving part is moving at right angles to the direction of the jet and when the jet is completed through the aperture of the moving part, this part is stopped and is locked in position by the jet. The jet is projected from a fixed nozzle and registers with a particular part of the rotor so that the rotor is stopped in a particular position.

Fluid pressure driven impellers have long been in use for a variety of purposes. In these devices the fluid pressure from the nozzle is either intercepted or deflected from its straight course and thereby causes motion, the motion is usually stopped by stopping the flow through the nozzle. By using a pair of nozzles deflected in opposite directions the impeller may be driven in opposite directions. If the impeller is driven the fluid discharged thereby through a tortuous passage retards the movement of the impeller.

In this invention any type of impeller may be used for driving the rotor and of course if the impelling fluid is shut off the rotor will stop, but it will not stop at a predetermined, selected position, further, it will not stop until its momentum has been expended. It is the purpose of the in-

vention to provide for driving the rotor, starting at any position and to stop it at selected positions by the application of fluid pressure from a jet that does not produce a driving effect, but instead produces only a stopping effect and locks the moving part to the fixed part as long as the pressure jet is maintained. For this purpose, in the stopped position the fluid pressure jet is not impeded or deflected to cause motion, instead it is maintained in a straight line in the direction in which it is projected and when the nozzle of the rotor intercepts this straight line the pressure jet resists its movement in either direction.

A simple way of securing this result is shown in the drawing in which the nozzles are arranged radially in the stator and give a radial direction to the fluid jet; the nozzle in the rotor is also arranged radially so that as it rotates it aligns with each nozzle of the stator, making a straight nozzle for the fluid jet through both the stator and the rotor. The force of this jet when the nozzles register stops the rotor and holds it in this position as long as the fluid pressure is continued. Other constructions equivalent to the radial construction are likely to be used and are fully contemplated thereby, especially where the motion is linear instead of rotary. The essential requirement is that the nozzle of the moving part register with the nozzle projecting the fluid pressure and that the former nozzle does not change the direction of the projected fluid.

The fluid pressure from the fixed nozzle gradually spreads out and loses its force as it leaves the nozzle. This is proportional to the pressure with which the fluid is projected. The nozzle 19 in the rotor is substantially the same size as the nozzles 25, but if the pressure is relatively low, or if 19 is spaced a considerable distance from the nozzles 25 it is apparent that in this case 19 should be larger in area than 25.

The air gap between the stator and rotor is used in the same sense as the air gap between the armature and its field in an electric generator. There is no mechanical drive between the stator and the rotor and there is no mechanical connection between the stator and the rotor to stop the rotor. It is apparent that the smaller the air gap the greater will be the efficiency of the fluid pressure stopping system.

The illustrations are mostly in diagram form, the mechanical construction admits of a variety of forms owing to the flexibility of the pneumatic operation. The system of control should be adapted to the particular use of the apparatus required and need not necessarily follow the illustrations shown.

Having thus described my invention, I claim:

1. A fluid motor comprising a stator, a rotor rotating about said stator, means for driving said rotor, a plurality of fluid pressure nozzles in said stator, a single corresponding nozzle in said rotor registering and aligning with the nozzles in said stator as it rotates, a source of fluid pressure and means controlling said fluid pressure to each nozzle in the stator and the nozzle in the rotor to stop the rotor when the nozzles are in alignment.

2. A fluid motor comprising a stator, a rotor rotating about said stator, means for driving said rotor in both directions, nozzles in said stator and a single corresponding nozzle in said rotor registering and aligning with the nozzles in the stator as it rotates, and means for stopping the rotor by fluid pressure in the registering nozzles.

3. A fluid motor comprising a stator, a rotor, means for driving said rotor to rotate it about

the stator, and a plurality of pressure fluid means in said stator located radially and cooperating with means in said rotor to stop the rotor in register with any of said stator means by the application of fluid pressure and means for damping the movement of the rotor as the point of register is approached.

4. A fluid motor and control system and comprising a stator having a nozzle, a rotor rotating about said stator and having a nozzle aligning with the nozzle of said stator, a driving nozzle deflected to drive said rotor by fluid pressure in one direction, a second driving nozzle deflected to drive said rotor in the opposite direction, a fluid pressure supply, a three-way valve controlling said fluid pressure supply to said driving nozzles to drive said rotor in either direction, and means for supplying fluid pressure to said aligning nozzles to stop said rotor.

5. A fluid motor and control system comprising a stator having a nozzle, a rotor rotating about said stator and having a nozzle aligning with the nozzle of said stator, a driving nozzle for said rotor, a fluid pressure supply, a conduit from said supply to said aligning nozzles, a valve connected to said conduit, a second conduit controlled by said valve connecting said supply to said driving nozzle and arranged to shut off the supply to the driving nozzle when the aligning nozzles are in register.

6. A fluid motor comprising a stator having a nozzle, a moving member separated from said stator by an air gap, and having a nozzle registering with the nozzle of the stator to lock the stator and the member against relative movement, means for driving said moving member and means for applying fluid pressure to said nozzles to lock them together when they register, said fluid pressure means being ineffective in retarding said movement until the nozzles come into register.

7. A fluid motor and control system comprising a pair of members separated by an air gap and movable relative to each other, a plurality of

nozzles in one of said members, each having a particular direction, a nozzle in the other member having the same direction as the nozzles in the first member and registering with each of the nozzles in the first member by said relative movement, a pressure fluid, and a valve controlling said pressure fluid to each nozzle to force the pressure fluid through the registering nozzles to stop the relative movement in a predetermined position.

8. A fluid motor comprising a pair of members separated by an air gap and movable relative to each other, means in one of said members for projecting a fluid pressure jet in a predetermined direction, a nozzle in the other member corresponding to and having the same direction as said fluid pressure jet and registering with said fluid pressure jet, said fluid pressure jet locking said members against movement as long as the jet is maintained.

9. A fluid motor comprising a pair of members separated by an air gap movable relative to each other, a nozzle in one of said members having a particular direction, a nozzle in the other member registering with the nozzle in the first member and having the same direction as the nozzle in the first member and having a tapering orifice opening towards the nozzle in the first member and means for forcing a fluid pressure jet through said nozzles to hold them in register.

10. A fluid motor and control system comprising a stator, a rotor rotating about said stator, a nozzle in said stator, a nozzle in said rotor registering and aligning in direction with the nozzle in said stator, a pressure fluid supply, a conduit connecting said supply with one of said nozzles to stop the rotor, a pair of independent valves in said conduit controlling said supply and so arranged that both valves must be in a predetermined position to establish the connection to said conduit.

MATTHEW H. LOUGHRISE.
